United States Patent

Des. 241,602
Patented Sept. 28, 1976

241,602

TOASTER-OVEN

Thomas E. Hanson, Philadelphia, Pa., and Stephen Maher, Portsmouth, Va., assignors to SCM Corporation, New York, N.Y.

Filed Apr. 16, 1975, Ser. No. 568,638

Term of patent 14 years

Int. Cl. D7—02

U.S. Cl. D7—93

FIG. 1

FIG. 2

III 3

III 4

III 5

FIG. 1 is a front perspective view of a toaster-oven showing our new design;

FIG. 2 is a top plan view thereof;

FIG. 3 is a front elevational view thereof;

FIG. 4 is a left side elevational view thereof;

FIG. 5 is right side elevational view thereof;

FIG. 6 is a rear elevational view thereof; and

FIG. 7 is a bottom plan view thereof.

We claim:

The ornamental design for a toaster-oven, as shown.
